United States Patent

Des. 241,625
Patented Sept. 28, 1976

241,625

CLOCK OR SIMILAR ARTICLE

James O. O'Brien, 2101 Hawk Lane,
Rolling Meadows, Ill. 60008

Filed Mar. 3, 1975, Ser. No. 554,648

Term of patent 14 years

Int. Cl. D10—01

U.S. Cl. D10—8

FIG. 1

FIG. 2

FIG. 1 is a front elevational view of a clock or similar article showing my new design;

FIG. 2 is a top plan view thereof, the bottom being flat, plain and unornamented.

I claim:

The ornamental design for a clock or similar article, substantially as shown and described.
